**COMBINED AMPLIFIER, TUNER, PHONOGRAPH
AND CASSETTE PLAYER**

Naoki Tominaga, Moriguchi-shi, Osaka, Japan, assignor
to Sanyo Electric Co., Ltd., Moriguchi-shi, Osaka,
Japan

Filed June 28, 1971, Ser. No. 157,800

Term of patent 3½ years

Int. Cl. D14—03

U.S. Cl. D56—4 B

FIG. 1

FIG. 2

FIG. 3

FIG. 4

FIG. 1 is a top, front, perspective view of a combined amplifier, tuner, phonograph and cassette player showing my new design, with a clear plastic cover in place;

FIG. 2 is a similar top, front, perspective view thereof, with the clear plastic cover removed;

FIG. 3 is a top plan view thereof, with the clear plastic cover removed; and

FIG. 4 is a rear, bottom, perspective view thereof, with the clear plastic cover removed from the side opposite that of FIGS. 1 and 2.

Portions of the figures have been diagonally lined to indicate transparency, and portions have been stippled to indicate contrast in appearance.

I claim:

The ornamental design for a combined amplifier, tuner, phonograph and cassette player, as shown and described.
